ATTORNEY

UNITED STATES PATENT OFFICE.

ADOLF JOSEPHS, OF SCRANTON, PENNSYLVANIA, ASSIGNOR OF TWO-FIFTHS
TO MAX ROSENBLUTH, OF WILKES-BARRÉ, PENNSYLVANIA.

IRONING-TABLE.

SPECIFICATION forming part of Letters Patent No. 612,905, dated October 25, 1898.

Application filed December 16, 1897. Serial No. 662,135. (No model.)

To all whom it may concern:

Be it known that I, ADOLF JOSEPHS, a citizen of the United States, residing at Scranton, in the county of Lackawanna and State of Pennsylvania, have invented certain new and useful Improvements in Ironing-Tables; and I declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to that class of ironing-tables which are adapted to be folded up and set away when not in use; and the objects of the invention are to furnish a more convenient form for such table and to render 20 them strong and more serviceable generally.

To this end the invention consists of the novel arrangement, construction, and combination of the several parts, as herein set forth, and illustrated in the accompanying 25 drawings, forming a part of this specification.

In the drawings, Figure 1 shows a side elevation of my device when set ready for use, showing in dotted lines the operation of the top board of the device. Fig. 2 is a view of 30 the same, showing in dotted lines the operation of the frame or legs of the device. Fig. 3 is an end elevation of the same. Fig. 4 is a top view of the same. Fig. 5 is a top view of the framework and supports, having the 35 top board removed. Fig. 6 is a detailed view of one of the braces used in the construction of the device. Fig. 7 is an under side view of the ironing-table when folded up to be set away.

40 Similar letters of reference refer to similar parts throughout the several views.

In the drawings, A designates the top board of the device, which is supported by the framework constructed of the braces B B, C C, and 45 D D, pivotally joined by means of the cross-pieces H and G, so as to permit of their being opened into the Z-shaped framework supporting the top A or of being folded down flat against the board A, as shown in Fig. 7. The 50 legs B B are also joined by means of the cross-

strip J, having a peg or stud at K, onto which the spring S is hooked by means of the strip T, having the holes t t.

The stand or framework is prevented from collapsing by means of the braces E and F, 55 which are constructed of rods bent in the shape of three sides of a rectangle and hooked into the holes e' e' by means of the hooks e e, the part opposite the hooks being adapted to engage with the notches f f in the members 60 C and D. The legs D D are also connected at their upper ends by the strip L, into which is set the pair of small rubber stops l l, which are adapted to render the board noiseless when dropped onto that end of the frame. 65

On the top of the wider end of the board A is the iron-holder N, having two apartments o and p, which are adapted to receive the flat-iron M. It is fastened to the board by means of the pegs n n, extending into holes in the 70 top of the board A. Directly underneath the apartment o of the iron-holder the board A is attached to H by means of screws or bolts h h. The upper ends of the members C C are beveled at b, so as to permit of the upward tilting 75 of the small end of the board A and so as to form a stop to prevent it from tilting too far.

The operation of the device is now readily explained. The spring S, which is attached 80 to the broader end of the board A at s, is hooked at K to such a tension that when the flat-iron M is placed in the space p the weight of the iron, added to the strength of the spring, tilts the board A to the position shown in 85 full lines in Fig. 1, thus permitting the operator to adjust tubiform garments to the board with both hands, and the garment being adjusted if the flat-iron M is picked up the board A immediately falls level into position 90 shown in dotted lines, Fig. 1. When it is not desired to tilt the board, the flat-iron M may be set on N at o. The garment having been ironed, the flat-iron is again set at p, when the garment may be removed by both of 95 the operator's hands and the board remains ready for another garment to be put in place and always adjusts itself for ironing purposes as soon as the flat-iron M is picked up to be used.

Having thus described my invention, what I claim as new, and desire to secure by Letters Patent, is—

1. In combination with an ironing-table, the iron-stand N secured on one end thereof, by means of pegs set into holes on the top of said table, said iron-stand consisting of two apartments one of which is located directly over the point at which the top of said ironing-table is pivotally joined to the framework thereof; and the top of said table so adjusted that when a flat-iron is set in one apartment of the iron-stand N, the top of the table will lie flat on its framework, and when a flat-iron is set in the other apartment of said iron-stand the top of the ironing-table is tilted so as to permit of the adjustment to it of tubiform garments, substantially as specified.
2. An ironing-table consisting of the frame members B B C C and D D joined together and braced by means of the adjustable braces

E and F, the board A secured to the cross-piece H pivotally secured to the upper ends of the members B B and C C, the cross-piece L joined to members D D and stops l l fixed therein, the spring S, and stud K on the cross-piece J, to which stud the spring S, may be hooked by means of the plate T having the holes t, t; together with the iron-holder N having two apartments and secured to the board A with one of its apartments, over the point of attachment of said board to the cross-piece H, and the other apartment beyond said attachment, all arranged for joint operation in the manner specified, and for the purposes set forth.

In testimony whereof I affix my signature in presence of two witnesses.

ADOLF JOSEPHS.
